US0D1095419S

(12) **United States Design Patent** (10) **Patent No.:** **US D1,095,419 S**
(45) **Date of Patent:** **** Sep. 30, 2025**

(54) **CHARGING STATION FOR ELECTRIC VEHICLES**

(71) Applicants: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(72) Inventors: **Zhiyong Zhao**, Beijing (CN); **Song Gao**, Beijing (CN); **Jietao Gao**, Beijing (CN)

(73) Assignees: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(**) Term: **15 Years**

(21) Appl. No.: **35/520,957**

(22) Filed: **Apr. 25, 2024**

(80) **Hague Agreement Data**

Int. Filing Date: **Apr. 25, 2024**

Int. Reg. No.: **DM/237060**

Int. Reg. Date: **Apr. 25, 2024**

Int. Reg. Pub. Date: **May 24, 2024**

(30) **Foreign Application Priority Data**

Apr. 12, 2024 (CN) 202430205732.9

(51) **LOC (15) Cl.** **13-02**

(52) **U.S. Cl.**

USPC **D13/107**

(58) **Field of Classification Search**

USPC D13/103, 107, 108, 110, 118, 119, 184, D13/199

(57) **CLAIM**

The ornamental design for a charging station for electric vehicles, as shown and described.

DESCRIPTION

3. Charging station for electric vehicles

4. Charging station for electric vehicles

3.1: Perspective

3.2: Perspective

3.3: Front

3.4: Back

3.5: Left

3.6: Right

3.7: Top

3.8: Bottom

4.1: Perspective

4.2: Perspective

4.3: Front

4.4: Back

4.5: Left

4.6: Right

4.7: Top

4.8: Bottom

(Continued)

Design Nos. 3 and 4 show charging stations for electric vehicles to different embodiments of the present design.

1 Claim, 16 Drawing Sheets
